CLAIM

The ornamental design for a snorkel mask as shown and described.

DESCRIPTION

FIG. 1 is a front elevational view of a snorkel mask showing my new design;

FIG. 2 is a right side view thereof;

FIG. 3 is a top plan view thereof;

FIG. 4 is a perspective view thereof;

FIG. 5 is a second perspective view thereof; and,

FIG. 6 is a third perspective view thereof.

The left side view not being shown is symmetrical with the right side view.

The broken lines illustrate portions of the snorkel mask that form no part of the claimed design.

1 Claim, 6 Drawing Sheets
